Primary Examiner — Omeed Agilee

Assistant Examiner — Michael Hoffman

(57) **CLAIM**

The ornamental design for a biometric electromagnetic scan skin bodysuit as shown and described.

DESCRIPTION

FIG. 1 is a front elevated perspective view of a biometric electromagnetic scan skin bodysuit showing my new design;

FIG. 2 is a rear bottom perspective view thereof;

FIG. 3 is a front view thereof;

FIG. 4 is a right side view thereof;

FIG. 5 is a left side view thereof;

FIG. 6 is a rear view thereof;

FIG. 7 is a top view thereof; and,

FIG. 8 is a bottom view thereof.
